Anthony J. Kina

UNITED STATES PATENT OFFICE.

THOMAS E. MURRAY, JR., OF BROOKLYN, NEW YORK.

RADIATOR.

Application filed August 8, 1925. Serial No. 48,929.

My invention aims to provide an improved design of radiators having a high efficiency in proportion to their size and having other advantages referred to in detail hereinafter.

5 The accompanying drawings illustrate an embodiment of the invention.

Fig. 1 is a plan;

Fig. 2 is a side elevation;

10 Fig. 3 is a horizontal section on the line 3—3 of Fig. 4;

Fig. 4 is a side elevation of an alternative embodiment of the invention.

According to Figs. 1 and 2 the vessel for the heating water, steam or other fluid is 15 composed of parallel lengths 1 and 2 of piping connected at one end by a bend 3 and provided with any usual or suitable accessories for admitting and discharging the heating fluid.

20 A radiating structure is applied to the heating vessel by welding, soldering or equivalent engagement and is made of a sheet metal plate or plates bent in such a way as to be conducive to high efficiency. In plan

25 (Fig. 1) the radiating structure comprises plates 4 approximately transverse to the length of the vessel, the plates 4 being connected alternately at their inner and outer edges by short longitudinal plates 5 and 6.

30 The transverse plates 4 and connecting plates 5 and 6 may be formed by bending a single sheet to the required number of convolutions for each side of the radiator; or by using a number of separate plates each comprising a

35 few convolutions, and uniting said plates to each other to make a radiating structure of the desired length, or they may be formed in various other ways. The plates in this way form vertically extending flues for the

40 passage of the air about the heating vessel and in contact with the radiating structure.

In elevation also the plates are bent as shown in Fig. 2, the upper half 7 extending obliquely in one direction and the lower half

45 8 obliquely in the opposite direction so as to form a zig-zag path for the ascending columns of air in the flues. Thus the air will travel a longer distance in contact with the radiating surfaces, will be forced to impinge

50 against the sides of the flues in their upward movement, and will move more slowly than through straight vertical flues; thus securing a greater heating efficiency.

The metal can be stamped to the shape 55 shown in Figs. 1 and 2 and to various other similar shapes or it may be made in sections

like the parts 7 and 8; the upper edge of one joined to the lower edge of the other. The best material for this structure is copper or cuprous metal in various alloys, these metals 60 being better adapted for radiating purposes than the more common iron and steel. Their increased conductivity and malleability make it possible to provide such a radiating structure of very thin copper sheets and to 65 get the same efficiency out of a structure so much smaller than an equally efficient structure of iron or steel as to counterbalance, at least in a large measure, the increased cost of copper.

70 In Figs. 1 and 2, I have assumed the pipe 1, 2, 3 to be the ordinary round pipe generally made of iron or steel, though it may also be of copper or cuprous metal. Where the latter is to be used for the heating vessel, however, the vessel may be made of the more efficient shape shown in Figs. 3 and 4. Here the vessel 9 is made of thin sheet metal, the vessel itself being high and narrow in cross-section so as to secure maximum contact with the heating fluid. It is enlarged and rounded to ordinary tubular form at one end 10 for connection of an admission valve and at the opposite end 11 for connection to another section of the radiator.

75 Figs. 3 and 4 also show the use of a radiating structure consisting of a plurality of zig-zag sections similar to those of Fig. 2 and indicated as a whole by the numerals 12, 13 and 14. These may be made separately 80 and welded together, the lower edge of one to the upper edge of the next, or similar multiple-zig-zag shapes may be made of a sheet or sheets which are continuous from top to bottom. The vessel 9 is engaged by the radiating structure 12, and similar vessels 15 and 16 are engaged by the structures 13 and 14.

85 The ends of the several vessels are provided with bends and couplings to form a continuous passage for the heating medium. Or 100 several such vessels may be connected in parallel, instead of in series as shown; that is with an inlet pipe connecting with the one end of each vessel and an outlet pipe with the opposite end of each vessel. The radiator plates form lateral braces for the sides of the heating vessels, and may be supplemented by auxiliary braces of any sort, permitting the use of very thin flexible sheet metal.

105 The invention is well adapted to indirect and similar heating systems in which a

forced draft is used. In that case a plurality of radiators like Fig. 2 or Fig. 4 may be arranged side by side or one above another and the air forced through the zig-zag passages.

The radiator may be equally used for cooling air by circulating cold brine or the like through the pipes so that the latter become a heating element only in the negative sense, that is, they extract heat from the radiating structure and induce a flow of the cool air downward through the flues similar to the upward circulation of air induced by the passage of steam through the pipes.

Various modifications of the design and arrangement shown may be made by those

skilled in the art without departing from the invention as defined in the following claim.

What I claim is:

A radiator comprising a heating vessel and a radiating structure engaging the same, said radiating structure comprising relatively thin sheet metal formed to provide spaced substantially vertically extending zig-zag enclosed flues, containing therein the heating vessel, said flues being so constructed as to provide corresponding zig-zag open flues within the inner and outer boundaries of said enclosed flues.

In witness whereof, I have hereunto signed my name.

THOMAS E. MURRAY, JR.
